UNITED STATES PATENT OFFICE.

GEORGE R. SELEY, OF SAN DIEGO, CALIFORNIA.

AERIAL TOY.

Application filed April 15, 1924. Serial No. 706,727.

To all whom it may concern:

Be it known that I, GEORGE R. SELEY, a citizen of the United States, residing at San Diego, in the county of San Diego and State 5 of California, have invented certain new and useful Improvements in Aerial Toys, of which the following is a specification, reference being had to the accompanying drawings.

10 This invention relates to toys, and particularly to an aerial toy in the nature of an aerial top.

The general object of the invention is to provide a very simple device of this character which, when it is rotated, will rise in the air, and so constructed that it will carry with it a fire-cracker, and also so constructed that as it rises it will make a whistling sound.

20 My invention is illustrated in the accompanying drawings, wherein:—

Figure 1 is a perspective view of my improved toy;

Figure 2 is a vertical sectional view 25 thereof.

Referring to the drawing, 10 designates a spindle and mounted upon the spindle is a sleeve 11 which projects above the upper end of the spindle so as to form a socket 12 30 in which a fire-cracker 13 may be carried. Also mounted upon the spindle so as to rotate therewith are a pair of opposite, reversely inclined wings or blades 14 which are apertured at 15, and disposed in said 35 apertures are the short, closed-ended whistling members 16. These are forced tightly into the apertures. When the top is spinning and rising into the air, these members 16 will produce a whistling noise. I do not 40 wish to be limited to any particular shape

for these members, as they might have other forms than relatively short, hollow, close-ended cylinders, but I have found that these produce the best effect. A socketed handle 17 is used for initially supporting the spindle, this socketed handle being provided with oppositely disposed, vertical slots 18 at diametrically opposite points, through which a cord 19 passes.

With a construction of this kind, the socketed handle is supported in the hand, the cord being wound upon the spindle, and then the cord is pulled rapidly in the usual way and this causes the rotation of the spindle and as it rotates the spindle rises into the air. If the fire-cracker is initially lighted, the fire-cracker will explode in the air and thus the toy may be rendered very amusing, particularly so during occasions like the Fourth of July.

I do not wish to be limited to the details of construction and arrangement of parts, as it is obvious that these may be changed in many ways without departing from the spirit of the invention.

I claim:—

A toy of the character described comprising a spindle having reversely inclined wings, a socketed handle for supporting the spindle, a cord whereby the spindle may be initially rotated, there being a sleeve surrounding the spindle and extending above the same to form a socket adapted to receive a fire-cracker, the wings being provided with members adapted to cause a whistling noise as the wings are rotated.

In testimony whereof I hereunto affix my signature.

GEORGE R. SELEY.
